CHARLES J. HUBER, OF BALTIMORE, MARYLAND, ASSIGNOR OF ONE-HALF TO FLYNN AND EMRICH COMPANY, OF BALTIMORE, MARYLAND, A CORPORATION OF MARYLAND

COMBUSTION METHOD

Application filed March 2, 1927. Serial No. 171,939.

In the development of stoking methods and apparatus, particularly within the last few years which have witnessed the enactment of smoke ordinances and the rapid advance in fuel prices, the trade has demanded the maximum efficiency in heat and power production from a given amount of coal and the reduction of smoke to the greatest possible extent. The achievement of these ends is dependent upon the accomplishment of a single result, i. e., the complete combustion of the fuel both as to the solids, and the vapors and gases given off by the solid fuel as it is brought to the temperature of combustion.

With the underfed type of stoker, with which many of the large plants are equipped, and forced draft, this has been accomplished to a considerable degree of perfection, but the overfed type, to which the present invention relates, and natural draft, have advantages as to simplicity and cheapness and ease of operation which have prevented their displacement by the underfed type and the use of forced instead of natural draft, but previously to the development of the present method of combustion the overfed type has proved deficient in the points just emphasized. It has been particularly difficult in the overfed type to achieve complete combustion of the fine particles of carbon and vapors and gases given off by the fuel, principally as it is heated up to the temperature of combustion, but also during combustion, so that the escape of a certain amount of smoke and the loss of a considerable proportion of the actual heat content of the fuel has been unavoidable.

The fuel most commonly used in boiler furnaces is bituminous coal which may be termed a two element fuel consisting of vaporizable matter and carbon. The necessity for the admission of air from above as well as through the fuel bed in the burning of such fuel is well recognized, the air admitted through the fuel bed being known as primary air and that admitted above the fuel as secondary air. The invention relates to a more efficient and scientific method of burning this fuel having particular reference to the admission of primary and secondary air and the combination of both with the vapor-

izable portions of the fuel to produce substantially complete combustion, resulting in the maximum of heat and developing the highest capacity of the furnace with the use of natural draft, it having been proven in actual practice that by the use of this method a thirty to forty percent increase of the steam output from a given boiler can be obtained without alteration of the stack or otherwise increasing the draft or the size of the furnace.

The invention may be aptly termed a two cycle method of handling a two element fuel. In accordance with the method of the invention the fuel is first heated, separating the volatile portions of the fuel from the solid and passing air over the fuel thus heated mixing air with the vaporized portions of the fuel at the instant of distillation and in the correct proportions. The air and gases being at this time, i. e., at the time of mixing, at a temperature above the kindling temperature of the mixture are completely burned and the solid fuel is ignited by the burning of the vaporized materials before it is deposited on the fuel bed.

The ignited solid fuel still containing a portion of the vaporizable material is then deposited on top of a bed of burning fuel. Over this a draft of secondary air is passed; mixing with the remainder of the gases distilled by contact of the newly fed fuel with the high temperature of the fuel bed, effecting complete combustion of all vaporizable material. The fuel bed composed of burning solid fuel is fed gradually backward, agitated and aerated by the admission of primary air from below so that all the fuel comes in contact with the primary air and there is a surplus of unburned heated air to complete the combustion of the gases over the fire, the passage of the same through the fuel being facilitated by agitation and the fine ash being dropped as the fuel progresses backwardly through the furnace, the clinker and unburnable solid matter being deposited at the rear and being dropped at intervals into the ash pit.

In the accompanying drawings I have illustrated an apparatus by means of which the method of the invention may be practiced to

55

advantage, the same being shown in operation in accordance with the steps of the method constituting the invention.

In the drawings:

5 Figure 1 is a vertical central section showing the entire apparatus in operation in accordance with the method.

10 Figure 2 is a section transverse to the plane of Figure 1 and looking forwardly, i. e., to the left in Figure 1.

15 Referring to the drawings by numerals, each of which is used to indicate the same or similar parts in the different figures, the apparatus as shown comprises a furnace structure 1 including an arch structure 2 at the front extending across the furnace and composed as to its bottom portion of heavy blocks 3 of fire brick or resistive ceramic material so arranged that the bottom face 4 of the arch 20 extends upwardly and to the rear from the feed opening 5. Beneath the feed opening is the coking shelf 7, also of heavy ceramic resistive material as fire brick, the members 3 and 7 serving as heat storing or reflecting 25 members which receive heat by direct radiation from the fire, store it and transmit it to the fuel.

30 The feed opening 5 and the hopper 8 preferably extend across the entire width of each heating unit or furnace so as to form a layer of fuel at 9 on the coking shelf and a curtain of fuel at 10 where the ignited fuel drops from the shelf, the curtain of fuel and the shelf extending across the furnace exposing 35 the greatest possible area of fuel surface to the action of air currents and to the passage of the air currents through the burning fuel, as hereinafter described. The fuel heated and ignited, as hereinafter described, is fed 40 from the shelf by the operation of the coal pusher 11, which is reciprocated by means of any suitable gearing actuating the crank 12 and connecting rod 14 which is in turn connected to the pusher, as shown, or in any 45 suitable manner.

50 The illustration, Figure 1, includes a transverse air passage 15 in the arch above the fire brick heat storing and radiating members 3, the air passage being heated by the waste heat from the furnace and led downwardly and forwardly from the transverse passage 15 into fore and aft passage 16 directly over the fire bricks and forwardly from this passage into vertical passages 17 by 55 which it is discharged through air inlet opening 18 into the furnace cavity immediately above and in contact with the fuel on the coking shelf 7.

60 In Figure 1 I have shown air openings 27 and 28 beneath the coking shelf and forward of the lower rear edge 19 thereof and particularly forward of the front portion 20 of the bed of burning fuel on the grate whereby air is admitted forward of the fuel bed and be- 65neath the coking shelf and passed through

70 the more or less variable and intermittent curtain of freshly ignited fuel at 10 and in contact with the fuel pile or front 20 of the fuel bed, which consists of freshly ignited fuel at 21 just dropped on the burning and partially consumed fuel bed, the air being thus combined with the particles of solid carbon which are liberated from the freshly ignited coal in the form of smoke and consuming the same, and the air not thus burned being heated and passing upwardly in combination with the combustion gases in the complete burning of which the supply of air thus admitted combines with and assists the supply of air admitted from above the shelf.

75 The apparatus further includes a grate 30 which is preferably inclined downwardly and to the rear, as shown, and composed of rocking bars 32 which are preferably of segmental cross section, being pivoted by means 80 of journals 33 at the vertex of each segment and having arcuate outer swinging surfaces 34 in contact with, or substantially in contact with, the sharply curved rear surface 35 of the next bar to the front, which curves are 85 concentric with the axis of the bar. These bars are slotted and are arranged in series of alternate bars, each bar having a depending arm 36 which is pivotally connected to a sliding link 37, there being one of such links for 90 each set of bars, all the bars of each set being thus pivotally connected to the same sliding link 37.

95 The two sets of bars are oscillated alternately either at regular intervals by means 100 of a continuously operating motor and selective timing mechanism, indicated in a general way at 40, and connecting rods 42, or the apparatus may be operated manually, the links being for this purpose connected to any suitable actuating mechanism, as the manually operated actuating operating means shown at 41, the member 41 being a socket to receive a hand lever. Beyond and somewhat below the rear and lower end of the grate is a drop bar 43, hinged at the forward end at 44 and supported at the rear on a link 45 which, in the normal position, is substantially upright, being pivotally connected at its upper end at 46 to the rear edge of the drop bar and pivotally connected at its lower end to a third sliding bar 47. By pulling the forward end of the bar 47, sliding it in a forward and slightly upward direction, the drop bar is 110 swung downwardly dropping the clinkers 115 and accumulated material into the ash pit.

120 In the practice of the method which is the subject of the invention, it being assumed that the stoking grate or stoker is covered with a thick bed of burning fuel, the hopper 8 is kept filled with a supply of fuel which is ordinarily bituminous coal, the same being fed through the feed opening 5 at the bottom of the hopper from time to time at the will of the operator, or otherwise, or in any suitable 125 130

manner as by the actuation of the pusher 11. The feeding operation, as described, it being noted that the advanced position of the pusher is well forward of the rear edge of the fuel supporting surface of the coking shelf, maintains at all times a supply of fuel at 9 on top of the coking shelf. The fuel on the shelf remains undisturbed between the strokes of the fuel pusher, the regular practice being to actuate the pusher for a single stroke at intervals dependent on the amount of fuel consumed.

The portion of the fuel thus fed to the shelf and remaining thereon from one stroke 15 to the next of the fuel pusher is exposed not only to the radiation of the fire, but to the heat stored in the heavy fire brick shelf 7 which is transmitted to the fuel by conduction the shelf being during full operation of 20 the furnace maintained at a white heat, and to the heat of the arch, which is an efficient heat storing member, as described, which heat is transmitted to the coal by radiation, it being understood that the arch is also 25 normally maintained at a white heat by the radiation of the fire to which it is directly exposed. While each charge of fuel thus supported on the arch is exposed to the highest temperatures which can be resisted by 30 resistive solid materials, as the fire brick composing the shelf, without destruction, it is further subjected to the action of a draft of air entering by the passages 17, the air current being heated by waste heat from the 35 upper and outer portion of the arch above the heat storing members 3. The high temperature to which the coal is thus subjected results in quick distillation of the volatile materials which are given off together with 40 considerable quantities of finely divided solids, ordinarily termed smoke, resulting from the destructive distillation of the tarry portions of the fuel.

In the previous practice the presence of 45 green coal on the fire with an insufficient supply of air caused these products to be passed up the flue, resulting in the discharge of smoke and noxious gases.

In accordance with the method of the 50 present invention, the finely divided solids and gases are immediately consumed by mixing with the draft of hot air introduced through the passages 17, the whole being above the temperature of ignition for the 55 gases and vapors the mixture is immediately burned. There is preferably a sufficient excess of air over that required for this purpose to ignite the partially coked fuel left on the shelf, the fuel being above the kindling 60 temperature. As particularly illustrated in Figure 2, the hoppers, coking shelves 7 and the layer and curtain of fuel, extend the full width of the furnace. The supply of fuel on the shelf having been thus partially coked 65 and ignited and the pusher having been with-

drawn and more green coal having dropped from the hopper in front of the pusher, the pusher being again advanced after a convenient interval corresponding to the heat being generated and, therefore, to the fuel 70 burned, the new supply of green fuel immediately in front of the pusher displaces the partially coked and ignited fuel on the shelf and causes a considerable portion of the latter to pass over and fall from the rear edge of 75 the shelf onto the fire, forming the curtain 10 already referred to. In this connection it is important to note that the stream or curtain of partially coked and burning fuel thus dropped on the fire extends across the 80 entire width of the furnace. As the fuel falls from the coking shelf in the ignited and highly heated condition described, it is subjected to a further draft of pure unburned air entering from beneath and forward of the coking shelf, or at least forward of the rear lower edge 19 of the coking shelf and the fuel pile. This air enters either from the ash pit or through the fire door by way of passages 27, 28, the fire door being mainly 85 for emergency access to the furnace and insurance against shut down. The air thus admitted passes through the curtain and over the coal pile, coming in contact with each piece of coal and the latter being in a highly heated condition the air mingling with the heated gases and suspended solid particles, assures complete combustion of the gases and suspended solids, eliminating smoke and noxious 90 fumes.

It is important to note that the air draft as admitted passes in close contact with the front of the pile of burning fuel on the grate at 20, taking up and mingling with and burning, in the high temperature of the furnace, the suspended solids and volatile matter given off on this surface of the fire, which is necessarily composed almost entirely of newly admitted fuel which is, however, partially coked and fully ignited, as 100 aforesaid.

The subjection of the highly heated fuel on the coking shelf by direct radiation and by conduction and radiation from the coking shelf, to a draft of heated air from above whereby it is ignited and then dropping it on top of the fire subjecting it as it falls and when it first lands on the fire to a further draft of air from beneath the coking shelf, partially cokes and completely ignites the fuel, depriving it of most of its volatile matter and completely burns the gases and suspended solids or smoke from the green fuel so that this portion of the smoke is eliminated and the fuel bed on the grate, instead of containing from time to time quantities of green fuel which are ignited on top of the fuel bed and burned in the back of the furnace with an insufficient air supply, is composed at all times of completely ignited fuel 115 120 125 130

which is further broken up from time to time as it is advanced down the grate permitting air to pass through the fuel bed completing the combustion begun on the coking shelf.

5 The manner of treating the fuel bed contributes an important element to the process whereby complete combustion is attained. By rocking at intervals first one and then the other set of alternate rocking stoker bars 13 32, the fuel is not only advanced step by step downwardly and to the rear as combustion progresses, but the fire is continually broken admitting the air from beneath the grate through the stoker bars to all points in the 15 fuel bed whereby the process of combustion is carried on uniformly throughout the body of the fuel on the grate. The action of the bars also serves in breaking up the fuel to further facilitate the admission and passage 21 of air therethrough by dropping the ash at all points on the grate, the unburnable material, as clinkers, being moved onward down the grate and finally deposited on the drop bar 43 from which they are dropped from 23 time to time into the ash pit—completely disposing of all materials introduced as and with the fuel.

While many efforts have been made to obtain complete combustion, eliminating 30 smoke and obtaining the greatest possible portion of the heat actually contained in the fuel, and while it is understood that the access of air or oxygen to every particle of the fuel, solid, vaporous and gaseous, is necessary for 35 complete combustion, and many efforts have been made to accomplish this result, it is believed that previously to the present invention no method has been devised whereby by feeding coal to the top of the fire, and particularly with natural draft, complete burning 40 of the finely divided suspended solids or smoke, gases and burnable solid unvaporizable materials has been attained, and the result in the present instance is believed to be due to the combination of steps whereby the fuel is highly heated on the coking shelf by the radiation of heat stored in the arch, the conduction and radiation of heat stored in the coking shelf and the direct radiation of 45 heat from the fire, and at the same time subjected to a draft of hot air and, as it is dropped on the fire, in the highly heated and ignited condition is further subjected to a draft of air from forward and beneath the coking shelf which is passed through and over the fuel as it falls and immediately after it has landed on the fire, whereby a fuel bed composed entirely of burning coal containing no green fuel at any time, is maintained. 50 The continual advancement and breaking of the fire providing for the admission of air at all points and the dropping of the ash contribute to an important extent to the whole result whereby complete combustion 55 is attained.

I have thus described specifically and in detail a method of combustion in accordance with my invention, and an apparatus by means of which the same may be practiced in order that the method of applying the invention may be clearly understood, however, the specific terms herein are used descriptively rather than in a limiting sense, the scope of the invention being defined in the claims.

75 What I claim as new and desire to secure by Letters Patent is:

1. The method of burning coal in a furnace which consists in maintaining a bed of completely ignited and burning fuel, breaking the bed throughout its extent continually and passing air through it, dropping the fine unburnable residue, presenting a supply of green fuel and maintaining the same within the furnace above the fire at the forward end and extending across the entire width of the fuel bed at the front, heating the same by conduction, radiation and reflection from the fire to a temperature above the kindling point of the fuel and driving off gases and vapors therefrom, admitting a supply of heated air above the fuel supply thus maintained and passing it over the fuel as it is heated, mixing the same with the gases and vapors given off from the newly heated fuel supply at a temperature above the point of ignition of said gases and vapors, burning the same and igniting the fuel supply thus presented, dropping the supply of burning fuel on the front end of the said bed of burning fuel on the fire across the entire width of the furnace, admitting air from below said fuel supply forward of the fuel bed and passing the air over the forward end of the fuel bed in contact with the recently deposited burning fuel and through the said dropping fuel causing the air to pick up and mingle with the gases and finely divided solid matter being released from the newly deposited burning fuel, burning the gases and completing the ignition of the fuel whereby a bed of fuel, all of which is fully ignited, is maintained throughout the length of the fire.

105 2. The method of burning coal in a furnace which consists in maintaining a bed of completely ignited burning fuel, presenting a supply of green fuel and maintaining the same within the furnace above the fire at the forward end, heating the same above the kindling point of the fuel by the conduction, radiation and reflection from the fire thus driving off the gases and vapors therefrom, admitting a supply of heated air above the fuel supply thus maintained and passing it over the fuel as it is heated, mixing the air with the gases and vapors given off from the newly heated fuel supply at a temperature above the point of ignition of said gases and vapors, thereby burning the gases and ignit- 110 115 120 125 130

ing the fuel supply and dropping the supply
of burning fuel on the front end of the bed
of burning fuel and moving the bed of burn-
ing fuel backward in the furnace as combus-
tion progresses.

5 Signed by me at Baltimore, Maryland, this
28th day of February, 1927.
